United States Patent Office

Des. 208,147
Patented July 25, 1967

208,147

KNOB

La Verne E. Clayton, Rockford, Ill., assignor to Amerock Corporation, Rockford, Ill., a corporation of Connecticut

Filed Nov. 14, 1966, Ser. No. 4,657

Term of patent 14 years

(Cl. D10—8)

FIG. 2 is a front view of the knob.

FIG. 3 is an enlarged sectional view taken along the line 3—3 in FIG. 2.

FIG. 4 is an enlarged sectional view taken along the line 4—4 in FIG. 2.

I claim:

The ornamental design for a knob, as shown.
